UNITED STATES PATENT OFFICE.

LOUIS A. M. PHELAN AND PAUL K. CRAMBLETT, OF BELoit, WISCONSIN.

ELECTRICAL APPARATUS.

Application filed December 22, 1922. Serial No. 608,504.

Our invention relates to electrical apparatus and it has special reference to improvements in electrical contact-making devices comprising spaced electrodes that are sealed into a closed container and are adapted to be brought into electrical conducting relation with one another through the agency of a movable conducting body, preferably a fluid such as mercury, likewise disposed in said container and which, on being tilted, is instrumental in performing the circuit-closing and circuit-opening functions of the device.

Our invention may comprise a flat elongated container preferably in the form of a glass tube that serves to enclose a pair of co-operating electrodes and a body of conducting liquid, such as mercury, the latter being adapted to bridge the electrodes within the tube. The tube is preferably disposed when installed to occupy normally a position neighboring on the horizontal and is intended to be suitably supported so that it may be tilted at the expense of very little energy in order to bring the conducting liquid into and out of bridging relation with the electrodes. The electrodes are sealed within the tube and as shown in this particular instance, the ends of the electrodes which are bridged by the body of conducting fluid are located adjacent one end of the tube.

A particular object of our present form of construction is to provide a container tube of such shape that it will serve to guide the conducting fluid in a definite channel. Such a construction is for the purpose of avoiding accidental contacting of the mercury with the electrodes due to splashing or other undesired movements of the body of mercury.

Another object of our invention is to provide an efficient and very simple form of electrode structure.

A further object of our invention is to provide a contactor device of the type indicated that will be economical to construct and which will possess a long life even when subjected to serious mechanical abuse.

Further objects will appear upon reference to the following description and accompanying drawings, in which—

Figure 1 is a vertical sectional view of one modification of device embodying our invention;

Fig. 2 is an end view of the device shown in Fig. 1;

Fig. 3 is a plan view of the device;

Fig. 4 is an enlarged detail view, partly in section showing the construction of the electrodes;

Figs. 5, 6, 7 and 8 are detailed cross-sectional views showing various possible modifications in the shape of the container.

The above described views, with the exception of Fig. 4, for clearness illustrate the invention in approximately twice its natural size. It may be here noted that the size of the container is an important consideration in its design because of the peculiar capillary and surface tension properties of the body of mercury.

The device as shown comprises in a general way a container 1 preferably formed of glass or a like material, electrodes 2 and 3 sealed and supported in the interior of the container tube 1 and a body of conducting fluid, such as mercury 4, which is free to flow along the bottom of the interior of the tube 1.

In the construction and design of the tube, great care should be taken to shape properly the various parts and to select the proper materials. It is preferable that the mercury be substantially free from impurities of all kinds. The electrodes 2 and 3 are preferably constructed of a pure metal, such as iron, which is not chemically affected by the mercury in the presence of the extreme temperatures of electrical arcs which may occur at the electrodes. The interior of the tube 1 is preferably evacuated and filled with a gas which does not combine in any way with the metal of the electrodes 2 and 3, or with the mercury in the presence of the intense heat. Hydrogen at substantially atmospheric pressure has been found to be satisfactory for this purpose. The tube 1 is evacuated and filled with the inert gas and sealed off at a tip 5.

The electrodes 2 and 3 may be formed at the ends of thin cylindrical sleeves 6 and 7, respectively, formed of a metal such as pure iron. The sleeves 6 and 7 are supported upon and serve to encase the inwardly extending ends of leading-in wires 8 and 9, respectively, which pass through the walls of the tube 1 and serve to bring the current through the glass walls of this tube without the possibility of any leakage of gas in or out of the tube at this point. Dumet wire is preferably used for these leading-in wires because of its desirable expansive properties when sealed in

glass. The sleeves 6 and 7 are extended for a slight distance along the leading-in wires 8 and 9, respectively, into the glass structure and thus serve to protect completely the 5 Dumet wire from exposure to the intense heat and gases within the tube 1.

Glass shanks 10 and 11 are formed on the walls of the tube 1 at a point where the wires 8 and 9, respectively, are sealed. 10 These shanks serve to support securely the electrodes 2 and 3 and provide for an extended sealing area between the wires 8 and 9 and the glass of the tube 1. It will be further noted that the glass shanks 10 and 15 11 are located at the ends of and at the upper side of the tube 1 so that they are remote from the body of mercury 4 and from any arcing that may occur at electrodes 2 and 3. Thus the possibility of injury by 20 heat to the sealed portions of the wires 8 and 9 is avoided.

The sleeves 6 and 7 are flattened at their ends in order to form electrodes 2 and 3 and also in order to close their ends against access of the mercury or gas within the tube 1. It will be noted that as shown, the electrode 3 is flattened in a direction parallel to the axis of the tube 1 and consequently parallel to the direction of the flow of the 30 body of mercury 4. The electrode 3 is also placed in an inclined position in respect to the body of mercury 4. The advantage of this particular form of flattened inclined electrode is to enable the electrode to offer 35 as little resistance as possible to the movement of the body of mercury 4 and to still retain a large contact area with the mercury. The resistance to the movement of the mercury into and out of circuit-making 40 position is a very important consideration in the construction of contactors of this character, which are designed to operate when tilted to only a very slight angle. In such cases the flow of mercury can be very 45 easily checked or entirely prevented.

By reference to Figs. 2 and 5, it will be noted that the tube is shown with a pronounced flattened cross section. With this design of the cross section of the tube, it 50 will be noted that sides 12 and 13 extend up vertically for a considerable distance in contact with the sides of the body of mercury 4 and thus serve to form a channel which guides the mercury and serves to 55 prevent any splashing or undesirable movements of the liquid. When the mercury flows in the channel of this type, its depth and stability can be much more easily controlled than when the mercury is placed in 60 the usual tube of circular cross section, such for example as indicated in Fig. 8. With the shape of tube shown in Fig. 2, practically all movement of the mercury is limited to that in a direction parallel to the axis of 65 the tube, which is the only direction of

movement which is essential for the proper action of the contactor.

In certain instances it is desirable to use a contactor of this type which will actuate upon being tilted only a small number of 70 degrees from the horizontal. In such cases, it is desirable to eliminate as much of the frictional effect as possible between the moving body of mercury and the container walls. It has been found that expedients 75 such as shown in Fig. 5 for stabilizing the mercury also have a slight tendency to retard the free flowing of the mercury even along its intended path. Accordingly it has been found to be advisable to modify the 80 cross-sectional shape of the container in order to secure the most desirable results under different tilting angles and stabilization requirements. In other words, it is 85 desirable to stabilize the mercury as much as possible without rendering its action too sluggish.

It has been found that mercury flows very freely upon a horizontal flat surface. The 90 design shown in Fig. 6 makes use of this fact since the lower side of the tube is formed as a flat surface upon which the mercury flows or rolls with considerably more freedom than on the rounded surface 95 shown in Fig. 5. The vertical parallel side walls for stabilizing the mercury are retained in Fig. 6 as in Figs. 2 and 5. Figs. 7 and 8 show forms of cross-sections which 100 respectively tend to permit still greater freedom and less stabilization of the mercury than do the above described structures.

As shown in Fig. 2, it is preferable to space the flat side walls of the container at an appreciable distance apart in order to prevent unnecessary sluggishness of the 105 mercury as when too closely confined. It will be further noted that considerable space at the upper side of the container is shown into which the mercury does not extend. This ample amount of space permits 110 the placing of the electrode leads and supporting shanks in a position where they will not interfere with the free flowing of the mercury when in its proper channel. Furthermore, the top wall as shown is at a 115 sufficient distance from the bottom wall to prevent the cooperation of these walls with the other walls of the container in holding or restraining the body of mercury, in case the container is tilted to an unusual angle.

A further feature in the preferred design shown in Fig. 1 is comprised in the use of rounded ends at 14 and 15. The use of these 120 rounded ends avoids the forming of a pocket-like recess by the side and end walls which would tend to cause globules of the mercury to stick at the ends of the container and thus prevent the proper action of the contactor. It will be noted that the 125 entire interior of the container also is con- 130

structed in a manner to be free from undesirable recesses that would tend to retain globules of mercury.

We desire that our invention be broadly interpreted and limited only by the prior art and by the scope of the appended claims.

What we claim as new and desire to secure by Letters Patent of the U. S. is:—

- 10 1. An electrode for contacting with a movable body of conducting liquid, comprising a tubular shell flattened at its end in a direction parallel to the movement of said body of conducting liquid.
- 15 2. In an electrical device, the combination of a supporting wire, and a tubular protecting shell surrounding said wire, an end of said shell extending beyond said wire and being crushed to close said shell and to form an electrode.
- 20 3. An electrical device comprising a container, a movable body of conducting liquid in said container, and electrodes in said container in the path of said movable body of liquid, said electrodes being formed of tubular shells, the ends of which are crushed to close said shells.
- 25 4. An electrical contactor comprising a container, a movable body of conducting liquid in said container, and electrodes in said container in the path of said movable body of liquid, one of said electrodes being

formed of a tubular shell flattened in a direction parallel to the direction of movement of said body of liquid.

35

5. An electrical contactor comprising a container, a movable body of conducting liquid in said container, and electrodes in said container in the path of said movable body of liquid, one of said electrodes being flattened in a direction parallel to the direction of movement of said body of liquid.

40

6. An electrical contactor comprising a container, a movable body of conducting liquid in said container, and electrodes in said container in the path of said movable body of liquid, one of said electrodes being flattened in a direction parallel to the direction of movement of said body of liquid and positioned in an inclined relation with respect to the surface of said body of liquid.

45

7. An electrical contactor comprising a container, a movable body of conducting liquid in said container, and electrodes in said container in the path of said movable body of liquid, one of said electrodes having much the larger portion of its surface contact area extending in directions substantially parallel to the direction of movement of said body of liquid.

50

In witness whereof, we have hereunto subscribed our names.

LOUIS A. M. PHELAN.
PAUL K. CRAMBLETT.
